SPEED RESPONSIVE COUPLING

Rolland M. Purdy, Bainbridge, N. Y., assignor to
 Bendix Aviation Corporation, New York, N. Y.,
 a corporation of Delaware

Application May 7, 1945, Serial No. 592,387

14 Claims. (Cl. 64—25)

1

This invention relates to couplings, and more particularly to means for connecting two rotating parts so that automatic, angular adjustments of said parts may be effected during rotation thereof.

Among the many uses of this invention is its particular application to the timing of sparks produced by the ignition system of an internal combustion engine and the invention will be particularly described in connection with a mechanism suited to that particular use, but it is to be understood that this particular description is for purposes of illustration only and does not constitute a limitation within the natural scope of the invention.

It is an object of this invention to provide a novelly constructed coupling device which is adapted to automatically advance the spark of an internal combustion engine when a particular speed of rotation is reached and to automatically retard the spark when a different increased speed of rotation is reached.

Another object of the invention is to couple driving and driven shafts by a novel coupling that automatically changes the angular relation of the driving and driven shafts at particular speeds of rotation.

Another object is to provide a novel speed sensitive coupling between rotating parts, the sensitivity of which can be varied to make it operate at different speeds.

Another object is to provide novel means to control the movement of a centrifugal weight, and a further object is to obtain such control by changing the leverage of a controlling device on the weight.

A particular object of the invention is to provide novel means for simultaneously and equally adjusting a plurality of centrifugal weights.

The above and further objects and novel features of the invention will more fully appear from the following detailed description when the same is read in connection with the accompanying drawings. It is to be expressly understood, however, that the drawings are for the purpose of illustration only, and are not intended as a definition of the limits of the invention, reference for this latter purpose being had primarily to the appended claims.

In the drawings, wherein like reference characters refer to like parts throughout the several views,

Fig. 1 is a vertical section on the line 1—1 of Fig. 2, looking in the direction of the arrows;

Fig. 2 is a vertical section on the line 2—2 of

2

Fig. 1, looking in the direction of the arrows, the cover plate having been removed to expose the flyweights;

Fig. 3 is a vertical section on the line 3—3 of Fig. 1, looking in the direction of the arrows, the cover plate having been removed to expose the flyweights; and,

Fig. 4a is an end view of a heavy flyweight and Fig. 4b is an end view of a light flyweight, the weights being arranged to show a size relationship that may sometimes be employed.

Internal combustion engines are desirably operated at certain speeds with an advanced spark and at other speeds with a retarded spark. In the case of automobile engines the advance and retarding of the spark were originally accomplished by manual means, but more recently by automatic means. In aircraft engines it is also desirable upon certain occasions to operate with an advanced and on other occasions with a retarded spark.

This invention provides the ignition systems of such engines with novel speed sensitive mechanism that automatically advances or retards the spark when selected engine speeds have been reached, and contemplates novel means for altering the angular relation of driving and driven rotating members. In the drawings, the drive shaft of a magneto, timer, distributor or the like of an ignition system is indicated by the numeral 10. Upon this drive shaft there is a driving gear 11, a driven gear 12, and a rotary support 13 between them. Double ended bearing pins 14 are mounted in the support and carry gear segments 15 that are in mesh with the gear 11 and gear segments 16 that are in mesh with the gear 12. The gear segments 15 extend beyond the points of pivotal attachment to the pins 14 and form oppositely disposed flyweights 17 that are of relatively heavy construction. Gear segments 16 extend beyond the pins to which they are pivoted as flyweights 18 which, in the mechanism illustrated, are of relatively light construction as shown in Fig. 4. Annular cover plates 35 and 36 are mounted on the pins 14 by bolts 37 and serve to retain the flyweights on the pins.

The engine drive (not shown) meshes with the splines 19 of the gear 11 and rotates the latter; the rotative effort of the gear 11 against the gear segments 15 urges the flyweights 17 centripetally and forms in effect a positive driving connection that rotates the pins 14, the support 13, the gear segments 16, the gear 12 and the shaft 10 as a unit. However, when the speed of rotation has increased sufficiently the flyweights 17 move cen-

trifugally under the impulse of centrifugal force, the gear segment 15 walks about the gear 11 advancing the support 13 and all the mechanical connections that follow it, and imparting an angular advance to the driven gear 12, and to the circuit breaker cam or other mechanical device operated thereby. As the speed of rotation increases still further, the flyweights 18 are actuated to apply through gear segments 16 and gear 12, a retrograde motion whereby reverse adjustment of gear 12 and shaft 10 with respect to gear 11 will take place and the spark will be retarded. It will be understood that this relative angular adjustment can be availed of in either direction with this coupling, depending upon which is the driving and which is the driven gear.

Referring now to the novel construction of the embodiment of the invention that is set forth in the drawings, 10 indicates generally a drive shaft, of an instrument such as a magneto or ignition timer, having an abutment 20 formed on the shaft as a thrust bearing for the inner race of a ball bearing 21 that carries the bearing area 22 of the shaft 10. Outwardly of the said abutment and bearing area the shaft 10 is provided with splined portion 23 and a reduced smooth portion 24 that is screw threaded at its end for the reception of a nut 25.

The gear 12 is mounted on shaft 10 by inter-fitting internal splines that fit the splines 23 and is provided with external gear teeth adapted to mesh with gear segments 16. A washer 27 fits over the portion 24 of the shaft 10 and is brought up against a shoulder formed inside the gear 12. A bearing and spacing sleeve 28 is placed over the end 24 of the shaft and brought up against the washer 27 and the hub 29 of the annular support 13 is mounted upon the inner end of the sleeve so that a portion of the hub fits within the end of gear 12 and bears against washer 27. The gear 11 is mounted on the sleeve 28 with an inner annular flange circumscribing the hub 29. The parts of the mechanism just described are held in assembled relation by means of a thrust washer 30, a lock washer and the nut 25.

The central portions 31 of pins 14 are larger than the bearing portions at the ends thereof and are mounted fixedly on a single diameter of the support 13 in order that the parts of the apparatus may be in dynamic balance. The enlarged central portions 31 of the pins 14 project slightly beyond the faces of the support and constitute abutments that, together with the sleeve 28, give clearance to the parts of the assembly. The gear segments 15, 16 are spaced from the support 13 by the projecting parts 31 of the pins; the gears 12 and 11 are provided with clearance by the hub 29, which bears against the washer 27 and is of sufficient extent to provide clearance between the face of the support 13 and the gear segment 16; and the sleeve 28 provides clearance between the ends of gear 11, washer 30 and support 13.

Because of their inter-fitting splines, the gear 12 must rotate with the shaft 10, and because of the connection of the gears 12 and 11 with the support 13, the parts of the mechanisms will rotate as a unit despite the revolvable mounting of gear 11 and support 13 on the sleeve 28.

In order that the operation of the flyweights may be controlled, novel means are provided whereby they may be made to act at selected speeds of rotation. In the preferred form these

novel means provide for the application to the flyweights of equal maximum controlling force to set the speeds at which they operate and for adjustment by applying that force to the flyweights with different leverage. This novel controlling means also contemplates equal and simultaneous adjustment of each pair of weights.

Mounted at the circumference of the support 13 are adjustable abutment rings 40 and 41, having leaf springs 42 riveted thereto and bearing upon the outer surface of the flyweights so as to load them centripetally and hold them in a position in which the abutments 43 of each pair of the flyweights make contact with flat areas on the gear segments. The outer surfaces of the flyweights have portions that are preferably concentric with the abutment rings when in the centrifugally energized position, so that the maximum pressure of the springs 42 on the surfaces of such flyweights is always the same regardless of the position of the ring. Novel adjustability is obtained in this preferred structure by a change in leverage secured by moving the abutment ring with respect to the flyweights so that the springs travel over the surface thereof, the leverage of the spring being equal in each such position to the distance between the point at which it touches the flyweight surface and the center of the supporting pin 14. Each ring 40, 41 is made adjustable by a pair of mounting slots 44 in the mounting flange 46 thereof. The adjustability of each spring is determined by the length of its mounting slots. Mounting bolts 47 pass through each slot into seats in the support 13 and may be screwed down against lock washers and the mounting flange to hold the ring in adjusted position. A similar and separate mounting is provided for each ring. It will be understood, therefore, that the speeds at which the operation of the driving and driven members takes place is governed in part by the relative weight of the flyweights and in part by the leverage of the springs. By means of these two elements of control, the very widest selection of operating conditions can be secured.

Assuming now that power is being applied to the driving member 11, simultaneous and equal rotation of all parts will occur at speeds below those at which the heavy flyweights 17 are thrown outward by centrifugal force. As generally employed in the timing of aircraft magneto, the heavy flyweights act instantaneously and completely at a selected speed to give the pins 31, the support 13, the gear 12, the shaft 10 and the mechanism driven by it an abrupt and complete advance. Thereafter, as long as the speed of the engine is below that at which the lighter flyweights 18 become operative, the selected advanced setting of the magneto will be maintained. Under certain circumstances it is desirable to have a retarded spark under conditions of higher engine speeds. Therefore, the lighter flyweights may be of such weight and so controlled by the springs as to operate under the influence of centrifugal force to produce the desired retarding of the spark at the selected advanced speed. When that speed is reached, the lighter flyweights 18 turn the gear 12 in a direction opposite to that produced by the heavy flyweights, and the retarded position of the parts 12 and 10 will be maintained so long as such high engine speeds are in use.

In slowing down the engine from high speeds, a reverse series of operations occurs, the light

flyweights being thrown centripetally at the higher critical speed by the springs which bear upon them, advancing the driven gear 12 and the shaft 10. As the engine slows to the critical lower speed, the heavy flyweights are returned centripetally and the parts 13, 12 and 10 are again retarded.

There is thus provided novel coupling means for driving and driven members that is accurately responsive to speeds of rotation, that is adjustable so that automatic control will take effect at those speeds that are selected, and that is of such simple construction that it can be made by ordinary methods of manufacture. The apparatus is self-contained, self-operated, and requires a minimum of attention. It is adapted for use in many situations where automatic and limited change of the angular relation of driving and driven members is to be accomplished by speed responsive means.

Certain modifications may be made in the foregoing structure; for instance, the curved surfaces of the flyweights may be shaped to produce alterations in the effect of the springs, being so shaped in one instance to produce increasing spring pressure as spring leverage is increased, and in another case producing decreasing spring pressure. The flyweights may be changed at will to others of different weight to obtain changes in operating speeds. Substitute abutment rings having springs of different construction or strengths may be made available to alter the operating characteristics of the device.

Although only one embodiment of the invention is illustrated and described in detail, it is to be expressly understood that the same is not limited thereto. As will now be apparent to those skilled in the art, various changes, such as in the design and arrangement of the parts illustrated, may be made in the illustrated embodiment of the invention without departing from the spirit and scope of the invention. For a definition of the limits of the invention, reference is had primarily to the appended claims.

What is claimed is:

1. Speed sensitive mechanism of the class described comprising a rotatable support, a flyweight pivotally mounted on said support having means to turn a gear by motion centrifugally imparted, means to limit the centrifugally imparted motion of said flyweight comprising a circumscribing abutment ring, approximately concentric surfaces on said ring and said flyweight, spring means carried by said ring and bearing on said flyweight, and means providing for movement of the ring with respect to the flyweight to vary the point of application of the pressure of the spring means thereto.

2. A speed sensitive coupling for rotatable members comprising a rotatable support, a plurality of flyweights pivoted to said support, spring means for applying pressure to said flyweights to oppose the centrifugal motion thereof, and means comprising an annular member carrying said spring means and mounted on the said support for adjustment in a arcuate path concentric with the axis of said support for simultaneously and equally adjusting the said spring means with respect to each of said flyweights.

3. Speed sensitive mechanism of the class described comprising a rotatable support, flyweights pivotally mounted on said support having means to turn a gear by motion centrifugally

imparted, means to limit the centrifugally imparted motion of said flyweights comprising a circumscribing abutment ring engageable by said flyweights and mounted on said support for adjustment relative thereto in an arcuate path, concentric surfaces on said ring and said flyweights, and spring means carried by said ring and adjustable therewith to bear on different parts of said concentric flyweight surfaces.

4. Speed sensitive mechanism of the class described comprising driving and driven members, a rotatable support angularly movable relative to both said members, flyweights pivotally mounted on said support having gear segments engaged with said driving and driven members, said flyweights being loaded by springs mounted for movement independently of and bodily with respect to said flyweights to vary the leverage thereon for operation by centrifugal force at different speeds.

5. A speed sensitive coupling comprising a driving member, a driven member, a rotary support between said members, flyweights pivotally mounted in pairs on each side of said support having gear segments in mesh with said driving and driven members, respectively, and adjustable spring pressure applying means to apply spring pressure simultaneously to the flyweights of each pair at selected corresponding points thereon to oppose centrifugal motion thereof.

6. A speed sensitive coupling comprising a driving gear, a driven gear, a rotary support between said gears, flyweights pivotally mounted in pairs on each side of said support having gear segments in mesh with said gears, means to apply spring pressure to the flyweights to oppose centrifugal motion thereof, and means to change the points of application of said spring pressure to the flyweights whereby the centrifugal motion thereof may be opposed with selected leverage.

7. A speed sensitive mechanical drive comprising a driving gear, a driven gear, a rotatable support between said gears, flyweights pivotally mounted on the support having gear segments in engagement with said driving gear, flyweights pivotally mounted on the support having gear segments in engagement with said driven gear, spring means to oppose the outward motion of the flyweights, and means to vary the leverage of said spring means on said flyweights.

8. A speed sensitive mechanical drive comprising a driving gear, a driven gear, a rotatable support between said gears, flyweights pivotally mounted on the support having gear segments in engagement with said driving gear, means to limit the centripetal motion of the said flyweights, flyweights pivotally mounted on said support having gear segments in engagement with said driven gear, means to limit the centripetal motion of the said flyweights, abutment rings adjustably mounted on said support to limit the centrifugal motion of the flyweights, and spring means attached to said rings bearing upon said flyweights to oppose the centrifugal motion thereof.

9. A speed sensitive mechanical drive comprising a driving gear, a driven gear, a rotatable support between said gears, flyweights pivotally mounted on the support having gear segments in engagement with said driving gear and having mutually co-acting abutments to limit their centripetal motion, flyweights pivotally mounted on said support having gear segments in engagement with said driven gear and having mutually co-acting abutments to limit their centrip-

etal motion, abutment rings adjustably mounted on said support to limit the centrifugal motion of the flyweights, and spring means attached to said rings bearing upon said flyweights to oppose centrifugal force.

10. A speed sensitive mechanical drive comprising a driving gear, a driven gear, a rotatable support between said gears, flyweights of one weight pivotally mounted on said support having gear segments in engagement with said driving gear and having mutually co-acting abutments to limit their centripetal motion, flyweights of a different weight pivotally mounted on said support having gear segments in engagement with said driven gear and having mutually co-acting abutments to limit their centripetal motion, abutment rings adjustably mounted on said support to limit the centrifugal motion of the flyweights, and spring means attached to said rings bearing upon said flyweights to oppose centrifugal force.

11. A speed sensitive mechanical drive comprising a shaft, a driving gear mounted on said shaft for rotation with respect thereto adapted to receive and to transmit rotary motion from a source of power, a driven gear mounted on said shaft, a support mounted between said gears for rotary motion about said shaft, flyweights of one weight pivotally mounted on said support having gear segments in engagement with said driving gear and having mutually co-acting abutments to limit their centripetal motion, flyweights of a different weight pivotally mounted on said support having gear segments in engagement with said driven gear and having mutually co-acting abutments to limit their centripetal motion, abutment rings adjustably mounted on said support to limit the centrifugal motion of the flyweights, and spring means attached to said rings bearing upon said flyweights to oppose centrifugal force.

12. A speed sensitive mechanical drive comprising a drive shaft, a driving gear mounted on said shaft for rotation with respect thereto adapted to receive and to transmit rotary motion from a source of power, a driven gear mounted on and splined to said shaft, a support mounted between said gears for rotary motion about said shaft, heavy fly-weights pivotally mounted on said support having gear segments in engage-

ment with said driving gear and having mutually co-acting abutments to limit their centripetal motion, light flyweights pivotally mounted on said support having gear segments in engagement with said driven gear and having mutually co-acting abutments to limit their centripetal motion, abutment rings adjustably mounted on said support to limit the centrifugal motion of the flyweights, and spring means attached to said rings bearing upon said flyweights to oppose centrifugal force.

13. Speed sensitive mechanism comprising a shaft, a weight pivoted eccentrically of said shaft to be rotated therewith and having a surface of material extent concentric with the shaft and a spring bearing on said surface and mounted for bodily movement therewith and independently of any movement of the weight to vary the leverage of the spring on the weight.

14. Speed sensitive mechanism of the class described comprising a pivoted flyweight operable by centrifugal force, and spring means for controlling said flyweight and movable bodily with respect to and independently of any movement of said flyweight when the latter is in its innermost position to bear upon different parts of the flyweight at different distances from the pivotal axis thereof when so bodily moved.
